CLAIM

The ornamental design for a cutting tool, as shown and described.

DESCRIPTION

FIG. 1 is a perspective drawing of the cutting tool illustrating the design thereof;

FIG. 2 is a front view of the cutting tool of FIG. 1;

FIG. 3 is a top view of the cutting tool of FIG. 1;

FIG. 4 is a left side view of the cutting tool of FIG. 1;

FIG. 5 is a right side view of the cutting tool of FIG. 1;

FIG. 6 is a bottom view of the cutting tool of FIG. 1, and,

FIG. 7 is a rear view of the cutting tool of FIG. 1.

The broken line showing of the blade is for illustrative purposes only and forms no part of the claimed design.

FIG. 1

FIG. 2

FIG. 3

FIG. 4

FIG. 5

FIG. 6

FIG. 7
